UNITED STATES PATENT OFFICE.

JOHN P. MATTSON, OF MINNEAPOLIS, MINNESOTA.

SNAP HOOK.

Application filed November 8, 1923. Serial No. 673,618.

To all whom it may concern:

Be it known that I, JOHN P. MATTSON, a citizen of the United States, residing at Minneapolis, in the county of Hennepin and 5 State of Minnesota, have invented certain new and useful Improvements in Snap Hooks, of which the following is a specification.

My invention relates to snap hooks used 10 on harnesses, bridles, draft appliances and other devices where snap hooks are used.

The object is to provide a simple snap hook that can not be opened or closed accidentally.

15 In the accompanying drawing:

Fig. 1 is what may be termed a front edge view of my improved snap hook attached to a leather strap and engaged in the ring of a bridle bit.

20 Fig. 2 is a section about as on the line 2-2 in Fig. 1.

Fig. 3 is a portion of Fig. 2 with the hook proper in open position.

25 Fig. 4 is a detail front view of the hook 9 only.

Referring to the drawing by reference numerals, 5 is a portion of a bridle bit having at its end the usual ring 5^a. To illustrate 30 at least one of the uses of my snap hook I have shown it as engaged in said ring 5^a.

The snap hook comprises a body piece 6 having an eye 7 adapted to be secured to a leather strap 8, and a hook member 9 pivoted at 10 to the body piece near the 35 rear end of a longitudinal slot 11 formed therein. The pivoted end of the hook has a plain angular end face 12 between which and the nearest terminal 13 of the slot is inserted a slidable key 14 which prevents 40 accidental opening of the hook by resisting the corners 9^a of its flat end. The key has a shoulder 15 engaged by the swingable end 16 of a leaf spring 17, which has its other end 18 supported in a notch 19 in the body 45 piece. A small cross bar or bridge 20 in the slot gives tension to the leaf spring and also engages an offset 21 of the spring to hold it constantly with its end 18 in the notch 19.

50 When the hook is to be opened the operator pushes with a finger at the end 14^a of the key 14 until the latter gets into the position shown in Fig. 3, and thus presents its clearance 14^b diagonal to the heel 9^a of the hook 9, and thereby allows the hook to

be swung open. When open it will stay thus until closed by the hand, because the spring is not strong enough to close the hook as long as the heel 9^a is not in a position to be swung by the key 14 and its 60 spring, but rather to resist closing of the hook by standing against the surface 14^b. The hook might even swing so far open as to resist forcible closing, but such swinging is prevented by side shoulder 22 on the 65 hook stopping against the edges 23 of the slot in the body piece. A touch of the hand will however close the hook, and when closed or nearly closed the spring 17 and key 14 act automatically to lock it until the key is 70 again pressed or pushed into unlocking position. In other words the contact of the heel or part 14^c of the key and heel 9^a of the hook hold the hook closed. When heel 14^c is pushed away the hook is easily opened. 75

It will be noted that the key may have a notch 24 for the end of spring 17. It may also have a slight projection 25 adapted to rest in a notch 26 in the body piece either or both means will prevent undue forward 80 movement of the key 14 which might cause it to get separated and lost.

Other means may of course also limit the movement of the key but as they would be mechanical equivalents to the means shown 85 I consider it superfluous to describe them.

The device may be either drop forged or cast. In casting it no core is needed since the sand in the cope will easily lift out of the slight depressions 19 and 26 and the 90 sand in the flask will draw downward out of the groove 11.

What I claim is:

1. A snap hook comprising a body member having an eye for securing it in place of 95 service, said member having a longitudinal slot, a second member having a flat and angular end pivoted in the slot in spaced relation to the terminal of the slot nearest said eye, the other end of the second member 100 being hook shaped and arranged to close with its point against the free end of the body member, a key fitted to slide transversely in the slot snugly between the terminal thereof and the angular end of the 105 pivoted hook member, whereby the latter is normally held in closed position, a spring arranged to normally hold the key with the hook closed, said key having its rear end protruding through the slot to give a chance 110

- 2
- to push it endways when the hook is to be opened, said key having a clearance allowing the hook to be swung open when the key is sufficiently pushed against the resistance of its spring.
5. The structure specified in claim 1, and means limiting the forward movement of the slide.
3. The structure specified in claim 1, in which said spring is a leaf spring held by one end in the front end of the slot and having the rear end pressing against the key to push it into locking relation with the hook.
10. 4. The structure specified in claim 1, in which said spring is a leaf spring held by one end in the front end of the slot and having the rear end pressing against the key to push it into locking relation with the hook,
15. and said spring being readily detachable from the body member.
5. The structure specified in claim 1, said hook member of the device having one or more side shoulders arranged to stop against the body piece when the hook is 25 fully opened.
6. The structure specified in claim 1, said hook member of the device having one or more side shoulders arranged to stop against the body piece when the hook is 20 fully opened, and said key having an edge portion adapted to engage the pivoted end of the hook and prevent accidental closing of the hook when its shoulders are against the body piece.

35
In testimony whereof I affix my signature.

JOHN P. MATTSON.
